UNITED STATES PATENT OFFICE

100,602

DESIGN FOR A COMBINED ELECTRICAL RECEPTACLE AND PLUG CONNECTER

Raymond E. Patten, Bridgeport, Conn., assignor
to General Electric Company, a corporation of
New York

Application December 18, 1935, Serial No. 60,160

Term of patent 14 years

To whom it may concern:

Be it known that I, Raymond E. Patten, a citizen of the United States, residing at Bridgeport, in the county of Fairfield, State of Connecticut, have invented a new, original, and ornamental Design for a Combined Electrical Receptacle and Plug Connecter, of which the following is a specification, reference being had to the accompanying drawing, forming a part thereof.

In the drawing, Fig. 1 is a perspective view of a combined electrical receptacle and plug con-

necter showing my new design, and Fig. 2 is a perspective view showing the electrical receptacle and plug connecter separated. The two sides of the structure are alike. The rear side is flat.

I claim:

The ornamental design for a combined electrical receptacle and plug connecter, as shown and described.

In witness whereof, I have hereunto set my hand.

RAYMOND E. PATTEN.
